ABSTRACT OF THE DISCLOSURE

New coumarin derivatives useful as optical whitening agents and their use in the treatment of textile materials. The coumarin derivatives are compounds of the formula

wherein R₁ is a hydrogen atom or alkyl group containing 1-4 carbon atoms and R₂ is an alkyl group containing from 1 to 4 carbon atoms.

This invention is concerned with new chemical compounds of use as optical whitening agents especially in the whitening and/or brightening of polyamide, polyester and other synthetic fibres.

Optical whitening agents have in recent years found extensive use in the treatment of textile fibres, both in their preparation and during washing, and are designed in general to counteract the yellow or off-white colour which white textiles may develop. Such optical whitening agents also tend to improve coloured textiles as they impart a general brightness to them.

The present invention is based upon the discovery of certain coumarin derivatives which have particularly advantageous properties as optical whitening agents.

According to the present invention, there are provided compounds of the general formula:

wherein

R₁ represents a hydrogen atom or an alkyl group which is if desired substituted by a non-ionogenic and non-colour producing substituent; and

R₂ represents an alkyl group which is if desired substituted by a non-ionogenic and non-colour producing substituent.

As stated above, the compounds according to the invention have particularly advantageous properties as optical whitening agents. In particular, they have excellent brightening properties for polyamide, polyester and other synthetic fibres when applied from aqueous and aqueous detergent baths, and have especially favourable fluorescent properties with a most desirable shade of blue-violet fluorescence.

In compounds of Formula I in which R₁ and/or R₂ represents a substituted or unsubstituted alkyl group, the said alkyl group preferably contains from 1 to 4 carbon atoms and is advantageously a methyl, ethyl, or isopropyl group. When R₂ represents a substituted alkyl group, the substituent may for example be a halogen e.g. chlorine

atom; R₂ may thus represent a β -chloroethoxy group. Alternatively, the substituent may be a radical of formula —NR₃R₄ in which R₃ and R₄ represent alkyl groups, preferably such groups containing from 1 to 14 carbon atoms; R₂ may thus represent a group of formula —(CH₂)_nNR₃R₄ wherein n represents an integer from 1 to 4. Quaternised derivatives of such compounds are also compounds in accordance with the present invention. An especially preferred compound of Formula I is the compound in which R₁ represents a hydrogen atom and R₂ represents a methyl group.

For the purpose of treating textile fibres in general, the compounds according to the invention may be advantageously be incorporated into compositions comprising at least one compound of Formula I together with a solid or liquid carrier. Such compositions may for example be adapted for use in the washing of finished polyamide and polyester fibres, and can take of the form of solutions suspensions and dispersions of compounds of Formula I in appropriate liquid carriers such as for example, sulphonolane, dimethylformamide and dimethylsulphoxide. When dispersions are used, they conveniently include dispersing agents such as for example alkyl naphthalen sulphonates. Aqueous compositions may if desired also contain for example synthetic detergents, soaps or surface active agents. Alternatively the compositions may be solid form and comprise at least one compound according to the invention together with a solid synthetic detergent or soap as carrier. The compounds of Formula I may also be employed in the manufacture of synthetic fibres, e.g. by addition to compositions from which the fibres are prepared by spinning or extrusion.

The coumarin derivatives of Formula I may be prepared by any convenient method, but are advantageously prepared by one of the following processes:

35 (1) Reaction of a compound of formula

(wherein R₁ is as defined above and X represents a cyano group or a group such as for example a nitro group convertible to a cyano group) with an appropriate alkylating agent to a cyano group. The alkylating agent is conveniently a dialkyl sulfate (e.g. dimethyl or diethyl sulphate) or an alkyl iodide (e.g. methyl iodide or ethyl iodide). The compounds of Formula II used as starting material in the reaction can for example first be prepared as follows:

45 (a) Reaction of a compound of formula

55 with a compound of formula

60 or a functional derivative thereof.

(b) Reaction of a compound of formula

65 with a diazonium compound of formula

(c) Where R_1 represents a hydrogen atom, heating of α - (4' - cyanophenyl) - β - (2'',4'' - dimethoxyphenyl) acrylonitrile in the presence of an anhydrous Friedel-Crafts catalyst such as for example aluminium chloride. The α - (4' - cyanophenyl) - β - (2'',4'' - dimethoxyphenyl) acrylonitrile may if desired first be prepared by the reaction of p-cyanobenzyl cyanide with 2,4-dimethoxybenzaldehyde.

(2) Reaction of a compound of formula

(VII) 15

(wherein R_1 and R_2 are as defined above) with a compound of formula

(IV) 20

(wherein X represents a cyano group or a group such as for example a nitro group convertible to a cyano group) or a functional derivative thereof, and where necessary converting the group X to a cyano group.

(3) Reaction of a coumarin derivative of formula

(VIII) 25

(wherein R_1 and R_2 are as defined above) with a diazonium compound of formula

(VI) 30

(wherein X represents a cyano group or a group such as for example a nitro group convertible to a cyano group), and where necessary converting the group X to a cyano group.

Where R_1 represents a hydrogen atom, the compounds of Formulae III and VII are substituted benzaldehydes. 2,4-dihydroxybenzaldehyde (Formula III, $R_1=H$) may thus for example be used.

Alternatively compounds of Formula VII such as for example 2 - hydroxy - 4 - methoxybenzaldehyde may be used which upon reaction with 4-cyanophenylacetic acid or a functional derivative thereof yield directly a compound of Formula I. Where compounds of Formula I are obtained in which R_2 represents a group containing a tertiary amino radical, the tertiary amino radical can if desired be quaternised, for example by reaction with dimethyl sulphate, diethyl sulphate, methyl iodide or ethyl iodide as quaternising agent.

In order that the invention may be well understood the following examples (in which all parts are by weight) are given by way of illustration only:

EXAMPLE 1

p-Aminobenzonitrile (4.2 pts.) in aqueous hydrochloric acid (18%) (50 pts.) was diazotised with sodium nitrite (2.5 pts.) in water (10 pts.) at 0-5° C. The diazo slurry was added to a mixture of sodium acetate (11.4 pts.), 7-methoxy-coumarin (6.3 pts.), acetone (24 pts.) and cupric chloride (1.5 pts.) in water (5 pts.). The temperature of the mixture rose 20° C. and nitrogen was evolved. The mixture was heated to 30° C. and held at that temperature for 3 hours. The reaction mixture was then cooled, filtered and dried. The precipitate was recrystallised from aqueous acetone to yield a pale grey powder (4.4 pts.) of 3(4' - cyanophenyl) - 7 - methoxy - coumarin. $E_1^1=1010$ at 348 m μ . M.P 230-235° C.

EXAMPLE 2

p-Cyanobenzyl cyanide (142 pts.) and 2,4-dimethoxybenzaldehyde (166 pts.) are dissolved in methanol (1600 pts.), cooled to 50° C. and caustic soda solution (sp. gr. 1.5) (7.5 pts.) are added to the solution. α -(4'-cyanophenyl) - β - (2'',4'' - dimethoxyphenyl)acrylonitrile immediately precipitates. The reaction mixture is cooled to room temperature and the precipitate is collected, washed with ethanol and dried. Yield 235 pts., M.P. 199-200° C.

10 α - (4' - cyanophenyl) - β - (2'',4'' - dimethoxyphenyl)acrylonitrile (145 pts.) is refluxed in o-dichlorobenzene (1200 pts.) with anhydrous aluminium chloride (250 pts.) for 8 hours. The reaction mixture is then cooled, filtered and thoroughly washed with water. The crude product is then steam distilled to remove o-dichlorobenzene. The product is then filtered, washed with water and dried. The product is 3 - (4' - cyanophenyl) - 7 - hydroxy - coumarin, yield 135 pts., M.P. 315° C.

15 3 - (4' - cyanophenyl) - 7 - hydroxycoumarin (135 pts.), anhydrous potassium carbonate (100 pts.), dimethyl sulphate (100 pts.), and methylethylketone (2500 pts.) are refluxed for 9 hours. At the end of the reaction the solvent is distilled off and the residual solid boiled with water (4000 pts.). The solid is then filtered and dried. The 3 - (4' - cyanophenyl) - 7 - methoxy - coumarin thus obtained is recrystallised from 35% acetic acid. M.P. 230° C., E_1^1 1040 at 348 m μ .

20 The following compounds have been prepared by a process analogous to that described in Example 2:

		M. P. C°	E_1^1	λ_{max}
3-(4'-cyanophenyl)-7-ethoxycoumarin-----		106-8	966	350
3-(4'-cyanophenyl)-7-isopropoxy-coumarin-----		216-8	958	351

EXAMPLE 3

Aqueous baths are prepared containing 0.1 g./ litre of 3 - (4' - cyanophenyl) - 7 - methoxy coumarin, 3 - (4' - cyanophenyl) - 7 - ethoxycoumarin and 3 - (4' - cyanophenyl)-7-isopropoxycoumarin respectively.

In use terylene fabric is treated in the baths for ½ hour at the boil, the liquor ratio being 1:40. The terylene thus treated is subsequently rinsed and dried and is in the case of each of the baths much whiter and brighter than prior to the treatment.

I claim:

1. A compound of the formula

I

50 where in R_1 is selected from the group consisting of a hydrogen atom and alkyl groups containing from 1 to 4 carbon atoms, and R_2 an alkyl group containing from 1 to 4 carbon atoms.

55 2. A compound according to claim 1 which is 3(4'-cyanophenyl)-7-methoxy-coumarin.

3. A compound according to claim 1 which is 3(4'-cyanophenyl)-7-ethoxy-coumarin.

60 4. A compound according to claim 1 which is 3-(4'-cyanophenyl)-7-isopropoxycoumarin.
